HIGH INTERRUPTING CAPACITY FUSES HAVING
CASINGS OF INORGANIC MATERIAL

Frederick J. Kozacka, South Hampton, N.H., and Erwin Salzer, Waban, Mass., assignors to The Chase-Shawmut Company, Newburyport, Mass.

Filed June 19, 1964, Ser. No. 376,417

3 Claims. (Cl. 200—120)

This application is a continuation-in-part of our co-pending patent application Ser. No. 355,804, filed March 20, 1964 for Electrical Cartridge Fuses, and this invention is concerned with high interrupting capacity fuses.

It is one object of this invention to provide high interrupting capacity fuses having casings of an inorganic insulating material which fuses are not subject to the drawbacks and limitations of prior art fuses having casings of inorganic materials.

The most common inorganic insulating materials for making casings of electric fuses are glass, porcelain and steatite. The least desirable of these materials is glass because of its brittleness. A serious limitation of porcelain and steatite as casing materials for fuses resides in the fact that these materials require a firing operation during which operation they shrink, making it impossible to maintain the close tolerances which are necessary, or desirable, for fuse casings of fuse tubes. After the firing operation ceramic materials are very hard—steatite is then harder than glass—and for this reason it is possible to machine pieces of fired ceramics only by grinding with Carborundum or diamond wheels.

It is, therefore, another object of this invention to provide high interrupting capacity fuses having casings of inorganic insulating materials not subject to the aforementioned limitations of casings of glass, porcelain and steatite.

Under short-circuit current conditions fusion of fusible elements of fuses and arcing is a process in the nature of an explosion. Therefore the dynamic strength of a fuse casing is a matter of paramount practical importance. Dynamic strength requirements of a fuse structure having a required current carrying capacity can best be met by integrating a plurality of separate tubular casing structures each housing a separate fusible element and a separate body of arc-quenching filler into a structural unit. Such multiple fuse structures may be achieved by substituting for the conventional casing of a fuse a cylindrical block of a ceramic material having a plurality of axially extending bores of which each houses one of a plurality of fuse links connected in parallel into an electric circuit and of which each also houses a separate body of pulverulent arc-quenching filler. While multiple fuses of this character have a relatively high dynamic strength, they are subject to all the limitations and drawbacks of fuses having a casing of a ceramic material. These drawbacks can be avoided and the high dynamic strength inherent in the multiple unit design still achieved by integrating a plurality of conventional fuse structures each having a relatively small current carrying capacity by means of common terminal blocks into a unitary fuse structure having a relatively high current carrying capacity. Fuses of this character are disclosed and claimed in U.S. Patent 2,647,970 to Wm. S. Edsall et al., Aug. 4 1953 Current-Limiting Fusible Protective Device and U.S. Patent 2,653,203 to F. J. Kozacka, Sept. 22, 1953 Current Limiting Fuse, both assigned to the same assignee as the present invention. Multiple fuses of the kind disclosed in the two above referred-to patents are, however, relatively complex and difficult to manufacture and do not lend themselves to use in connection with inorganic casing materials.

It is, therefore, another object of this invention to pro-

2

vide multiple fuse structures within the above meaning which are not subject to the limitations and drawbacks of the above referred-to prior art multiple fuse structures.

If the spring biased contacts of a fuse holder are intended to bear directly against the end surfaces of a fuse structure the casing of the latter must be kept to relatively close tolerances, and must have a high degree of dimensional stability, and a relatively high compressive strength, for lack of any of these characteristics results in an undesirable, or intolerable, variation of the contact pressure from piece to piece of equipment. Combinations of fuse holders and fuses of the aforementioned kind are, therefore, ruled out wherever the casing of the fuse is made of a fired ceramic material, for the tolerances of such materials are too large to achieve the required uniformity of contact pressure. Combinations of fuse holders and fuses of the aforementioned kind are also ruled out wherever the casings of the fuses consist of fiber; for fiber is a material whose dimensional stability is far too small to achieve the required uniformity of contact pressure.

It is, therefore, another object of this invention to provide electric fuses having casings of a relatively inexpensive inorganic insulating material which has the physical characteristics required to allow the contacts of a fuse holder to engage under pressure the end surfaces of the fuse structure.

The present invention as well as the aforementioned patent application Ser. No. 355,804 are concerned with fuses having casings of precompressed asbestos cement. The term precompressed asbestos cement as used in this context is intended to distinguish a specific kind of asbestos cement from other kinds of asbestos cement. The term precompressed asbestos cement is applied to identify a laminated, densified product obtained by bonding thin, soft, paperlike laminae (which may have been made on a paper making machine) under considerable pressure—such as 1,400 p.s.i.—into a unitary material, simultaneously removing a great deal of excess water. The process of making precompressed asbestos cement, or densified asbestos cement (which is known in the art) will be outlined below more in detail. Casings of precompressed asbestos cement can readily be machined. This makes it possible to manufacture fuse casings out of relatively thick sheets of precompressed asbestos cement by simple cutting or sawing and drilling operations. The geometry of such casings tends to increase dynamic strength if they are formed by prismatic blocks having a plurality of parallel bores each receiving one of a plurality of fuse links and a pulverulent arc-quenching filler. This, in turn, is conducive to great compactness for given rating requirements. The relatively great compressive strength of precompressed asbestos fiber cement coupled with the close tolerances to which that material can readily be machined make it possible to associate fuses having casings of precompressed asbestos cement with fuse holders having contacts directly engaging the end surfaces on the fuses and putting the casings of the latter under compression. As mentioned above, fuse casings of fired ceramic materials, while having a high compressive strength, do not lend themselves to application in such fuse holders because such fuse holders can be applied only if the spacing between the end surfaces of the fuses can be held to close tolerances, and because fired ceramic materials do not allow to achieve sufficiently close tolerances.

Since fuse holders having contacts which engage directly the end surfaces of a fuse structure make it possible to dispense with blade contacts on the latter, and to arrange the fuse holder contacts closer to the fuse structure, combinations of this nature of fuse holders and fuses

are conducive to both greater economy and greater compactness.

Providing a plurality of fuse-link-receiving bores in prismatic blocks of precompressed asbestos cement—the axes of the bores being arranged in planes parallel to two of the outer surfaces of the blocks—yields fuse structures which are relatively narrow and relatively deep. This is very desirable for a number of applications where there are no stringent limitations in regard to depth requirements, but stringent limitations in regard to width requirements. One such instance is the combination of fuses with automatic switches and/or circuit breakers, where fuses may have a depth commensurate to that of the automatic switch or circuit breaker, but should be relatively flat to achieve large spacings between the phases, or the poles, of an automatic switch or circuit breaker.

Fuses and combinations of fuses and fuse holders embodying our invention are illustrated in the accompanying drawings wherein:

FIG. 1 is a side elevation of a fuse embodying this invention;

FIG. 2 is a top plan view of the structure of FIG. 1;

FIG. 3 is a side elevation of another fuse embodying this invention;

FIG. 4 is a top plan view of the structure of FIG. 3;

FIG. 5 is a vertical section across another fuse embodying this invention taken along 5-5 of FIG. 6; and

FIG. 6 is a top-plan view of the structure of FIG. 5.

Referring now to the drawings, and more particularly to FIGS. 1 and 2 thereof, numeral 26 has been applied to indicate a prismatic block of precompressed asbestos cement. Block 1 is rectangular in cross-section and has a pair of rectangular end surfaces 26'. Block 26 further defines a plurality of bores 25 circular in cross-section and extending at right angles to end surfaces 26'. Fusible ribbon elements 24 of a high current-limiting action metal—copper or silver—is arranged within bore 25 in coaxial relation thereto. Fusible ribbon elements 24 of a high current-limiting action metal—copper or silver—is arranged within bore 25 in coaxial relation thereto. Fusible ribbon elements 24 are provided with a plurality of serially related points of reduced cross-section on necks (not shown in FIGS. 1 and 2). Bores 25 are filled with a body of quartz sand, as clearly shown in FIGS. 3 and 5. As a result of the use of quartz sand as arc quenching medium, and of the compactness of the device, block 26 may reach, or will reach, temperatures not permissible in fuses having casings of organic insulating materials. Since block 1 is made of precompressed asbestos cement it can safely withstand temperatures far in excess of those to which organic casing materials may be subjected. Precompressed asbestos cement is capable of safely withstanding temperatures of 600° F. for indefinite periods of time. The end surfaces 26' of block 26 are covered by congruent stampings 27', 28' of asbestos sheet and asbestos sheet stampings 27', 28' are, in turn, covered by terminal plates 27, 28 of metal. The latter have an angular flange which is intended to affix the fuse structure to a fuse holder. Asbestos stampings 27', 28' are provided with central slits for the passage of fuse links 24. Each of the lower ends of fuse links 24 may have a bend of 90° (not shown in FIGS. 1 and 2) spot-welded to the lower terminal plate 28. The upper terminal plate 27 has a plurality of circular depressions or recesses 22 intended to receive a small quantity of solder. The upper end of each fuse link 24 is threaded through a narrow hole in terminal plate 27 and soldered to the latter by a small quantity of solder neatly limited to the area of recesses or depressions 22. Terminal plates 27 and 28 are affixed to block 1 by means of self-tapping drive pins 29 projecting through terminal plates 27, 28 into end surfaces 26' of block 26. To this end block 26 is provided on the upper side thereof and on the lower side thereof with eight axial holes at the places where drive

pins 29 are intended to be located. These holes are not tapped, and the drive pins are driven into them by means of a suitable press. While subjected to the pressure of the press drive pins 29 rotate about their own axes, and while so rotating cut appropriate threads into block 26.

It will be apparent that this simple technique of affixing terminal plates cannot be applied in instances where the casing structure is made of a fired ceramic material since such materials are too hard to allow the use of self-tapping pins.

It will be apparent from FIGS. 1 and 2 that there are six fuse link and quartz-sand-receiving bores 25 in block 26 of precompressed asbestos cement. These six bores 25 in the block 26 shown in FIGS. 1 and 2 are arranged in two groups, each comprising three bores 25. There is one drive pin 29 in each corner of terminal plates 27, 28, and there are additional pairs of drive pins between contiguous pairs of bores 25. This even spread of fasteners 29 is of considerable importance since it fully meets the increased dynamic strength requirements of the structure of FIGS. 1 and 2 and does not call for drive pins of relatively large diameter tending to impair the mechanical integrity of block 26.

The structure of FIGS. 3 and 4 will be described below only to the extent that it differs significantly from the structures previously described. The prismatic block 30 of precompressed asbestos cement shown in FIGS. 3 and 4 defines three bores 31, 32, 33 having axes arranged in a common plane parallel to two of the outer surfaces of block 30. Bores 31, 32 house arrangements of fuse links and of quartz sand such as more fully described in connection with FIGS. 1 and 2. Bore 33 houses a blown fuse indicator mechanism, or striker pin mechanism, for indicating whether or not the fuse has blown, or for performing some mechanical duty such as, for instance, tripping of a circuit breaker, or load break disconnect, in response to blowing of the fuse. The structure housed in bore 33 of FIGS. 3 and 4 includes a restraining wire 34 of steel threaded through lower asbestos fiber stamping 35 and lower terminal plate 36 of metal and having one end clamped by screw 37 against plate 36. The upper end of restraining wire 34 is attached to the lower tab-shaped and perforated end of an indicator or striker pin 38. The latter is surrounded by a helical spring 39 biasing pin 38 and spring housing 40 in upward direction. The lower end of helical biasing spring rests against pot-shaped bore insert 41 having a perforation 42 for the passage of striker pin 38 and closing the upper end of bore 33. Restraining wire 34 is threaded at the lower end thereof through a little disc 43 of an elastomer forming a seal precluding the loss of any of the quartz sand filler 44 inside of bore 33.

Parts 41, 40, 38, 34 and 37 establish a conductive connection between the upper terminal plate 45 and the lower terminal plate 36. This current path has a high ohmic resistance and is shunted by the fuse links 24' in bores 31 and 32 establishing current paths of relatively small ohmic resistance between terminal plates 36 and 45. Therefore the current path formed by parts 41, 40, 38, 34 and 37 does not normally carry any significant current, virtually all the current being carried by the fuse links 24' in bores 31 and 32. Upon blowing of the fuse these fuse links 24' are severed and a significant current begins to flow through restraining wire 39, resulting in rapid fusion thereof. Now spring 39 is free to propel pin 38 and spring housing 40 out of bore 33 in block 30, indicating that the fuse has blown, or performing some auxiliary operation in response to blowing of the fuse.

The structure of FIGS. 5 and 6 comprises a prismatic block 46 of precompressed asbestos cement having two parallel bores 47, 48, each housing a fuse link 49, 50 and a body of quartz sand 51, 52. Terminal plates 53, 54 are secured to block 46 by self-tapping drive pins 55, and conductively interconnected by fuse links 49, 50. Each terminal plate 53, 54 is formed by two flange por-

tions of which one is horizontal and the other vertical. Each vertical flange portion supports a cylindrical rod or pin contact 56, 57 cooperatively engaging a tulip contact generally indicated at 58 and 59, respectively.

Regarding the product which has been referred-to above as precompressed, asbestos cement, the preparation of that product differs from and its preparation differs from the preparation, of other asbestos cement products. One of these differences resides in the fact that in making precompressed asbestos cement large quantities of excess water are being used, which are subsequently removed under considerable pressure in hydraulic presses before the asbestos cement is allowed to cure. Hence the term precompressed asbestos cement. The proportions of the ingredients, i.e. asbestos and hydraulic cement, may vary within broad limits. Thus a thin slurry may be prepared including 8 to 20% of Portland cement, about 15% of asbestos, and water. For this particular application it is desirable to use asbestos known as Chrysotil. The cement slurry may be processed on a paper making machine, resulting in the removal of some excess water through sieves. Further removal of excess water may be achieved by supporting the asbestos cement mixture on a support of felt. The sheets delivered by the paper making machine are cut to the desired size and stacked. Then a solid metal plate is arranged on the top of each stack and a wire net on the bottom of each stack. A number of such stacks are superimposed in a heavy hydraulic press and subjected to considerable pressure resulting in a further removal of excess water prior to curing of the stacks. The uniform plates of precompressed asbestos cement resulting from this process are cut to strips, whereupon the latter are cut to prismatic blocks and provided by means of gang operated drills with the required number of link-receiving bores.

It will be understood that we have illustrated and described herein preferred embodiments of our invention and that many alterations may be made in the details thereof without departing from the spirit and scope of our invention as defined in the appended claims.

We claim:

1. An electric fuse comprising in combination:
  - (a) a plurality of fusible elements of a high current-limiting action metal;
  - (b) a plurality of separate bodies of quartz sand each embedding one of said plurality of fusible elements;
  - (c) a pair of spaced terminal plates conductively connected by said plurality of fusible elements; and
  - (d) a prismatic block of precompressed asbestos cement having a pair of end surfaces and defining a plurality of bores extending at right angles to said pair of end surfaces, the axes of said plurality of bores being situated in a common plane parallel to a pair of outer surfaces of said block, each of said plurality of fusible elements and each of said plurality of bodies of quartz sand being housed in one of said plurality of bores, said pair of terminal plates covering said pair of end surfaces of said block; and
  - (e) self-tapping drive pins projecting through said pair of terminal plates into said pair of end surfaces of said block for securing said pair of terminal plates to said block.

2. An electric fuse comprising in combination:

- (a) a plurality of fusible elements of a high current-limiting action metal;
- (b) a plurality of separate bodies of quartz sand each embedding one of said plurality of fusible elements;
- (c) a pair of spaced terminal plates conductively connected by said plurality of fusible elements;
- (d) a prismatic block of precompressed asbestos cement having a pair of rectangular end surfaces and defining a plurality of bores extending at right angles

to said pair of end surfaces, the axes of said plurality of bores being arranged in a common plane parallel to a pair of outer surfaces of said block, each of said plurality of fusible elements and each of said plurality of bodies of quartz sand being housed in one of said plurality of bores; and

- (e) a plurality of pairs of self-tapping drive pins projecting through each of said pair of terminal plates into each of said pair of end surfaces of said block, said plurality of pairs of self-tapping drive pins including pairs of self-tapping drive pins arranged between contiguous ends of said plurality of bores.
3. An electric fuse comprising in combination:
    - (a) a predetermined number of fusible ribbon elements of a high current-limiting action metal;
    - (b) a pair of spaced terminal plates conductively connected by said ribbon elements;
    - (c) a prismatic block of precompressed asbestos cement having a pair of rectangular end surfaces and defining a plurality of bores extending at right angles to said pair of end surfaces and exceeding by one said predetermined number of fusible ribbon elements, said plurality of bores having a common median plane parallel to one pair of outer surfaces of said block, each of said fusible ribbon elements being housed in one of said plurality of bores and embedded in a body of quartz sand, said pair of terminal plates covering said pair of end surfaces of, said block;
    - (d) a blown fuse indicator in one of said plurality of bores, said one of said plurality of bores further housing a fusible wire element conductively connecting said pair of terminal plates and normally restraining said blown fuse indicator, and a separate body of quartz sand in said one of said plurality of bores embedding said fusible wire element; and
    - (e) self-tapping pins projecting through said pair of terminal plates into said pair of end surfaces of said block for securing said pair of terminal plates to said block.
